PAINT STRIPING DEVICE

David A. Wallace, Detroit, Mich., assignor to
 Chrysler Corporation, Detroit, Mich., a corpora-
 tion of Delaware

Application July 29, 1931, Serial No. 553,799

11 Claims. (Cl. 91—62.6)

This invention relates to an improved striping device.

Heretofore in applying paint stripes on articles with conventional striping devices, considerable difficulty has been encountered in starting the paint to flow at the commencement of a stroke immediately upon initial contacting of the pens of the device with the work, and in stopping the flow of paint when the pens are lifted at the end of each stroke. Attempts to remedy this condition have been made by providing valves for controlling the flow of paint which are operable by valve stems that protrude through and beyond the outlets of the pens. With such valve structures, and any other apparatus which relies upon linear movement, it is necessary to retain the nozzle in a disadvantageous position substantially normal to the surface upon which the stripes are being formed. The scraping contact of the valve stems with the work during movement through the stripe applying strokes frequently scratches the surface and forms streaks in the stripes.

The main objects of this invention are to provide a striping device which has improved means for starting the flow of paint to the striping pen upon application of the pen to the surface of an article and for stopping the flow of paint when the striping device is lifted from the surface of the article at the end of each stroke; to provide means of this character which permits the striping device to be held at an inclination to the surface of the work during operation without obstructing the outlet of the pen; to provide a swiveled nozzle in a device of this character which is universally tiltable in all directions relative to the body of the device; to provide improved means for yieldably holding the swiveled nozzle in axial alignment with the body portion; and to provide paint conducting passages in the

swiveled nozzle and body portion which do not communicate with each other when the nozzle is in axial alignment with the body portion, but which are adapted to be brought into communication with each other by tilting of the nozzle in any direction relative to the body portion of the device as the striping is applied to the work.

Further objects of the invention are to provide a swiveled nozzle in a device of this kind which has a pair of pens for forming spaced stripes; to provide separate passages in the swiveled nozzle for feeding a different colored paint to each pen, respectively; to provide separate passages in the body portion for supplying a different colored paint to each passage of the nozzle and which communicate with their corresponding passages

of the nozzle only when the latter is tilted at an inclination to the body portion so as to enable starting and stopping of the flow of paint to the pens as the latter are applied to and removed from the surface of the work, respectively; and to provide a swivel nozzle which rotates freely relative to the body portion during application of the pens to the surface of the work so as to equalize the pressure upon the pens.

An illustrative embodiment of the invention is shown in the accompanying drawings, in which:

Fig. 1 is a perspective view diagrammatically illustrating the manner in which my improved striping device is employed and the feeding of the paint thereto by gravity.

Fig. 2 is a vertical section showing a striping device embodying my invention in an inoperative condition.

Fig. 3 is a view similar to Fig. 2 showing a striping device in an operative condition.

Fig. 4 is a fragmentary perspective view of the striping device illustrating the manner in which pressure upon the striping pens is equalized.

Fig. 5 is a transverse section taken on the line 5—5 of Fig. 3.

Fig. 6 is a transverse section showing the parts of a striping device that embodies a modified form of the invention in inoperative relation.

Fig. 7 is a view similar to Fig. 6, showing the nozzle of the device in an operative position.

Fig. 8 is a transverse section taken on the line 8—8 of Fig. 7.

Fig. 9 is a vertical section of a striping device embodying a further development of the invention.

Fig. 10 is a transverse section taken on the line 10—10 of Fig. 9.

Fig. 11 is a transverse section taken on the line 11—11 of Fig. 10.

In the form shown in Figs. 1 to 5 inclusive, my improved striping device includes a tubular body portion 1 having a passage 2 for conducting paint, preferably fed by gravity, from a tank 3 through a flexible hose 4. The tubular body portion has an enlarged head 5 having an inner recess 6 in which a seat 7 is fixed. The seat 7 includes a convexed spherical surface 8 having an open circular groove 9 which is substantially concentric with the axis of the body portion 1. The groove 9 is connected by passages 10 with the passage 2 of the body portion.

Formed at the outer end of the enlarged head 5 is a recess 11 into which a nozzle 13 is extended. The nozzle 13 has a head portion 14 on its inner extremity which is provided with a convexed

110

spherical surface 15 that conforms with and abuts against the concaved spherical surface 8 of the seat 7. Formed in the nozzle is a passage 16 having one extremity open at the spherical surface 5 of the head 14 and having branch passages 17 leading to the outer extremity of the nozzle. Striping pens 18 communicate with the branches 17 and are threaded on the outer end of the nozzle. These striping pens have outlets 19 at their 10 extremity and adjacent tapered side portions 20.

The nozzle is tiltably mounted, or universally swiveled on the enlarged head 5 of the body portion 1 and is yieldably held against displacement by a sleeve 21 which is slidably mounted in the 15 recess 11 and which has a radial flange 22 that bears against a shoulder 23 on the head 14 of the nozzle. The sleeve 21 is yieldably urged inwardly by a coil spring 24 which bears between the flange 22 of the sleeve and the end of a closure, or cap 20 25 which is externally threaded on the enlarged head 5 of the body portion. The cap 25 is provided with an opening 26 which is substantially larger than the portion of the nozzle with which the cap registers so as to permit a limited universal wobble movement of the nozzle relative to the 25 body portion.

The spring 24 and sleeve 21 firmly hold the spherical surfaces of the head of the nozzle 14 and the seat 17 in firm contact with each other 30 and they also yieldably hold the nozzle substantially in alignment with the body portion, as illustrated in Fig. 2, so as to retain the inner open ends of the passage 16 in non-registering relation with respect to the circular groove 9. In the 35 form shown in Figs. 1 to 5, the inner end of the passage 16 is closed by that portion of the concaved spherical surface 8 of the surface 7 which is included within the circular groove 9.

In operation, the striping device is held at an 40 inclination to the surface of the work upon which stripes are to be applied, as illustrated in Fig. 3, and as the striping pens 18 are urged against the work with a slight pressure, the nozzle is tilted relative to the body portion sufficiently to bring the open inner extremity of the passage 16 into 45 registration with the open circular groove 9. When the parts are in this relation paint flows from the passage 2 of the body portion through the passage 16 of the nozzle to the outlets 19 of the striping pens. The striping pens are held at 50 an inclination to the surface of the work and rested upon their tapered side portions 20 and the outlets 19 of the pens are unobstructed during the movement of the device. When the nozzle is tilted 55 during the stripe applying strokes, the radial flange 22 of the sleeve 21 bears upon the shoulders 23 of the head of the nozzle at a substantial distance from the axis of the nozzle, as illustrated in Fig. 3, and considerable force is exerted on 60 the nozzle, tending to return it to its normal position in alignment with the body portion of the device. When the striping pens are lifted from the surface of the work at the end of a stroke, the sleeve 21 and spring 23 rapidly return the 65 nozzle to its normal position and immediately cut off the supply of paint to the pens so as to obviate dripping of paint upon the work or widening of the stripe at the end of each stroke of the device. The central portion 26 of the concaved 70 spherical surface of the seat 7 forms a sufficiently tight shell at the inner end of the passage 16 to prevent either paint or air from entering the passage 16. As a result, the paint which remains in the passage 16 after the nozzle has been returned to its normal position is prevented from 75

flowing out of the passage and is retained in readiness for the next stroke of the device.

In Figs. 6, 7 and 8 is illustrated a modified form of my improved striping device which is adapted to simultaneously form stripes of different colors. The structure of the device is mainly identical to that shown in Figs. 1 to 5 inclusive and corresponding parts of the structure are designated by the same numerals used in the description of Figs. 1 to 5. The tubular body portion 2, however, is provided with a pair of passages 27 and 28 for conducting differently colored paints respectively, and the nozzle 13 has a pair of passages 29 and 30 for feeding the differently colored paints to the striping pens 18. Formed in the concaved spherical side of the seat 8 are a pair of spaced outer grooves 31 which communicate with the passage 27 of the body portion through passages 32 in the seat 7. An inner circular groove 33, which communicates with the passage 28 of the body portion through passages 34, is provided at the central portion of the concaved side of the seat. The passage 29 of the nozzle has an outwardly extending end portion which normally registers with that part of the concaved surface of the seat which is located between the spaced grooves 31 and the open extremity of the passage 30 of the nozzle registers with that portion of the concaved side of the seat 7 which is inclosed within the inner circular groove 33 when the nozzle is in its normal position.

When the nozzle is tilted downwardly to the position illustrated in Fig. 7, by application of the striping pens to the surface of the work, the open end of the passage 29 registers and communicates with the outermost groove 31 and the open end of the passage 30 communicates with the upper side of the groove 33. If the nozzle were tilted upwardly from the position shown in Fig. 6, the open end of the groove 29 would register with the inner groove 31 and the open end of the passage 30 would register with the lower side of the groove 33. Regardless of the direction in which the nozzle is tilted, the open end of the passage 29 is brought into communication with one of the grooves which is supplied with paint of a different color from the passage 28 of the body portion.

In the form shown in Figs. 9, 10 and 11, the striping device includes a body portion 35 having passages 36 and 37 for conducting differently colored paints, respectively. Seated in a recess 38 in the enlarged head 39 of the body portion 35 is a seat 40 having a concaved side 41 against which a convexed extremity of a nozzle 42 is yieldably held by a coil spring 43 and a shiftable sleeve 44. The coil spring 43 bears between a cap 45 threaded on the enlarged head 39 of the body portion and a radial flange on the shiftable sleeve 43.

Formed in the nozzle 42 are passages 46 and 47 which communicate with striping pens 48 mounted on the outer extremity of the nozzle. The inner end of the passage 46 has a pair of branches 49 each of which communicate with a circular groove 50 formed in the spherical convexed extremity of the nozzle. The passage 47 has an open extremity which communicates with a groove 51 which is also formed in the convexed extremity of the nozzle. A passage 52 in the seat 40 communicates at one end with the passage 36 of the body portion and it registers at its other end with that part of the convexed extremity of the nozzle which lies between the grooves 50 when the nozzle is in its normal position. The seat 40 also has a passage 53 which communicates at one

end with the passage 37 of the body portion. The other end of the passage 53 registers with that portion of the convexed extremity of the nozzle which is inclosed within the circular groove 51, when the nozzle is in its normal position.

When the nozzle is tilted by application of the striping pens to the surface of the work at least one of the grooves 50 registers with the passage 52 of the seat 40 and permits paint of one color to flow from the passages 36 of the body portion to one of the striping pens. This tilting of the nozzle also brings the grooves 51 into registration with the outer end of the passage 53 which permits paint of a different color to flow from the passage 37 of the body portion to the other striping pen. When the striping device is lifted from the surface of the work the nozzle is returned to its normal position in alignment with the body portion and all of the grooves in the convexed extremity of the nozzle are rotated out of registration with the passages 52 and 53 and therefore the supply of paint to both nozzles is immediately discontinued.

Although but several specific embodiments of this invention have herein been shown and described, it will be understood that various changes in the size, shape and arrangement of parts may be made without departing from the spirit of my invention and it is not my intention to limit its scope other than by the terms of the appended claims.

What I claim is:

1. A striping device including a body portion having a face of curved contour and having a paint conducting passage therein leading to said curved face, a nozzle tiltably mounted on said body portion having a curved face fitting the curved face of said body portion including a striping pen and having a passage leading from its curved face adapted to communicate with the passage of said body portion only when said nozzle and body portion are in predetermined relative positions, and yieldable means urging said faces together for maintaining a sealed engagement therebetween and adapted to urge said nozzle and body portion from said predetermined relative positions for normally retaining said passages in non-communicating relationship.

2. A striping device including a body portion having a paint conducting passage therein, a nozzle universally swiveled on said body portion including a striping pen and having a passage adapted to communicate with the passage of said body portion only when said nozzle and body portion are displaced from a predetermined relative position, and a resilient member for holding the contacting faces of said nozzle and body portion in sealed relation and adapted to yieldably urge said nozzle relative to said body portion and toward said predetermined relative positions for normally retaining said passages in non-communicating relationship.

3. A striping device including a body portion having a curved face and a paint conducting passage therein leading to said face, a nozzle universally swiveled on said body portion including a shoulder and a face fitting the curved face of said body portion and having a passage leading from its face adapted to communicate with the passage of said body portion only when said nozzle and body portion are in predetermined positions, a rigid member shiftably mounted on said body portion and engageable with said shoulder, and a spring coacting between said member

and said body portion and yieldably urging said faces together and said nozzle relative to said body portion and away from said predetermined relative positions for normally retaining said passages in non-communicating relationship.

80

4. In a striping device, a body portion including a spherical swivel seat having a circular groove therein and a communicating passage for feeding paint thereto, and a nozzle universally swiveled on said seat including a spherical surface for normally closing said groove when said nozzle and body portions are in predetermined relative positions and having a passage adapted to communicate with said groove when said nozzle and body portions are displaced in any direction from said predetermined relative positions.

85

5. In a striping device, a body portion including a spherical swivel seat having a circular groove therein and a communicating passage for feeding paint thereto, a nozzle universally swiveled on said seat including a spherical surface for normally closing said groove when said nozzle and body portions are in predetermined relative positions and having a passage adapted to communicate with said groove when said nozzle is not in said predetermined positions, and means for retaining the spherical surface of said nozzle in sealed engagement with the swivel seat of said body portion and adapted to yieldably hold said nozzle and body portion in said predetermined relative positions for preventing the flow of paint to said nozzle.

95

6. In a striping device, a body portion having an end recess, a spherical swivel seat in said recess having a circular groove and a communicating passage for feeding paint thereto, a nozzle universally swiveled on said body portion including a head having a spherical seat conforming with and engaging the swivel seat of said body portion for sealing said groove and having a passage adapted to communicate with said groove when said nozzle is disposed at an inclination in any direction relative to said body portion, a sleeve slidably mounted in said recess and engaging the head of said nozzle, and a spring bearing upon said sleeve for retaining the spherical surfaces of said head in close fitting relation with said swivel seat and for yieldably holding said nozzle in alignment with said body portion.

100

7. In a striping device, a body portion including a concaved seat having an open groove therein and having a communicating passage for feeding paint to said groove, a nozzle swiveled on said body portion including a striping pen and having a convexed seat conforming with and abutting said concaved seat and having a passage adapted to register with said groove when said nozzle is tilted during application of said pen to the work, and yieldable means normally holding said convexed seat in sealing engagement with the open side of said groove and adapted to tilt said nozzle when said pen is lifted from said work so as to bring the passage of said nozzle and groove of said seat into non-communicating relation.

115

8. In a striping device, a body portion including a curved seat and having a passage open at said seat, a nozzle swiveled on said body portion having a passage and including a curved seat conforming with and abutting the seat of said body portion and having a circular groove communicating with the latter passage normally in non-registering relation with the passage of said body portion, a striping pen on said nozzle communicating with the passage thereof, said nozzle being tiltable in any direction during application

120

130

135

140

145

150

of said pen to the work for registering said groove and the passage of said body portion, and means for returning said nozzle to its normal position when said pen is lifted from the work.

- 5 9. In a striping device, a body portion having a pair of passages therein each for conducting a differently colored paint, a seat in said body portion having a pair of open circular grooves, each communicating with one of the passages of said 80
10 body portion, and a nozzle swiveled on said seat including a pair of striping pens and having a pair of passages one communicating with each pen and normally in non-registering relation with the grooves of said seat, and each adapted to register 85
15 with one of said grooves respectively when said nozzle is tilted in any direction during application of said pens to the work.

10. A striping device including a body portion having a passage therein, a nozzle swiveled on 90
20 said body portion tilttable in any direction relative thereto during application of said nozzle to a piece of work and having a passage normally spaced from the passage of said body portion when said nozzle is in a predetermined position
25 and adapted to register with the latter passage

when said nozzle is displaced in any direction with respect to said predetermined position, and means for returning said nozzle to said predetermined position so as to place said passages in non-communicating relation when said nozzle is lifted 95
from the work.

11. In a striping device, a body portion having a pair of passages therein, each for conducting a differently colored paint, a nozzle swiveled on 100
said body portion and universally tilttable in any direction relative thereto during application of said nozzle to a piece of work including a pair of striping pens and having passages communicating with said pens, each passage of said nozzle being non-communicative with a corresponding passage of said body portion when said nozzle is disposed in a predetermined relation thereto and adapted to communicate with a passage of said body portion when said nozzle is tilted in any direction relative to the latter, and means for returning said nozzle to said predetermined relation with said body portion when said pens are lifted from the work so as to discontinue the flow of paint.
